UNITED STATES PATENT OFFICE.

GEORGE W. JACKSON, OF CHICAGO, ILLINOIS.

METAL SHEET-PILING.

No. 888,899.

Specification of Letters Patent. Patented May 26, 1908.

Application filed September 3, 1907. Serial No. 381,053.

To all whom it may concern:

Be it known that I, GEORGE WASHINGTON JACKSON, a citizen of the United States, and a resident of Chicago, in the county of Cook and State of Illinois, have invented certain new and useful Improvements in Metal Sheet-Piling; and I do hereby declare that the following is a full, clear, and exact description thereof, reference being had to the accompanying drawings, and to the letters of reference marked thereon, which form a part of this specification.

This invention relates to improvements in metal sheet piling used as retaining walls for cofferdams or supporting the earthen walls of excavations, and refers more specifically to that kind of sheet piling comprising alternate sections of rolled metal bars or shapes which are constructed and arranged to have laterally interlocking, longitudinally guiding connection in such manner that each section, as it is driven, is guided into place by its interlocking or guiding engagement with an already driven adjacent section.

The invention consists in the matters hereinafter set forth and more particularly pointed out in the appended claims.

Among the principal objects of my invention is to provide a construction in metal sheet piling of such character as to assure waterproof joints between the sections or units of the piling, and thus prevent leakage of water through a retaining wall constructed of such sheet piling.

Other objects of the invention will appear from the description which follows:

As shown in the drawings:—Figure 1 is a perspective view of the protruding upper ends of a plurality of interlocked sections or units of sheet piling made in accordance with my invention. Fig. 2 is a fragmentary horizontal section thereof. Figs. 3 and 4 illustrate means for preventing the bolts, used to hold together the members of the piling, from turning. Fig. 5 is a horizontal section, similar to Fig. 2, illustrating a modification. Figs. 6 and 7 are perspective views of parts of one of the sections of the piling, showing another form of means for preventing the holding bolts from turning.

The sheet piling herein shown as embodying my invention embraces alternate sections or units which may be designated as simple and compound sections, one comprising a single rolled metal shape or bar and the other two rolled metal shapes or bars fastened to-

gether by bolts or the like, and providing between the two members, longitudinal spaces to receive interlocking parts of the single or simple sections of the piling, thereby providing guiding means to guide each section, as it is driven, from an already driven adjacent section.

The simple section of the sheet piling herein shown comprises an I-beam 10, while the compound section comprises two channel bars 11 11 arranged with their flanges 12 12 directed toward each other, but separated by longitudinal spaces to receive the webs of the I-beams. The two members of the compound section are secured together by bolts 13 13 which extend between and through bolt openings in the webs 14 14 of said channel bars. The flanges 15 15 of the I-beams 10 occupy the spaces inclosed by the connected channel bars, the oblique inner faces 15 15 fitting the oblique faces of the flanges 12 12 of the channel bars. The bolts by which channel members of the compound sections are secured together may consist of ordinary machine bolts. They are provided with the usual heads 16 16 and nuts 17 17, the latter engaging the screw threaded ends of the bolts. Said bolts extend through the marginal parts of the webs of the channel bars.

In accordance with one feature of my invention, means are provided to prevent said bolts from turning as the nuts are being tightened or loosened. As shown in Figs. 1 to 3 inclusive this is effected by the employment of plates 20 which fit against the lateral, exterior faces of the webs of the channel bars and are provided with opening 21 registering with the bolt openings in said webs. Said plates 20 are formed at the sides of the bolt openings with laterally extending lugs 22 which engage the heads 16 of said bolts in a manner to prevent the bolts from turning. The said lugs are formed by metal struck up from the body of the plates. As shown in Fig. 3 the lugs are located at the lateral sides of said openings, while in Fig. 4 they are located at the top and bottom of said openings.

In Fig. 6 I have shown two narrow bolt holding plates 23, which take the place of the single plate 20 of the previously described construction. Said narrow plates are provided with bolt head engaging lugs 22 made like and performing the same function as the lugs of the first described plates. In Fig. 7 I have shown another mode of preventing the bolts from turning, comprising angle bars 24

riveted to the exterior, lateral faces of the webs of the channel bars and arranged in parallel pairs, a bar of each pair being located on one side of each vertical row of bolt openings 5 of said web.

The bolt holding plates referred to serve, in addition to their function of holding the bolts from turning, as stiffening plates to strengthen the channel bars, thus permitting 10 the channel bars to be made of somewhat lighter metal when this construction is employed. The strengthening feature is somewhat emphasized in the bolt retaining or holding means shown in Fig. 7, embracing 15 the angle bars 24, the flanges of which extend laterally from the faces of the webs and constitute stiffening ribs.

In Fig. 5 is shown bolts 25, for connecting together the members of the compound sections, which are provided with square shank 20 portions 26 that engage angular openings in the adjacent webs of the channel bars. This form of bolt and its interlocking connection with the channel bar permits the omission of 25 the bolt holding means hereinbefore described, and is more specially adapted to lighter sheet piling.

Referring now to the construction by which watertight joints are provided between the several sections or units of my improved sheet piling, which construction constitutes the principal feature of the present 30 invention, the same is made as follows:

30 30 designate elongated cores, made of 35 wood or like material, which occupy the spaces between the webs of the channel bars of the compound sections. Said cores extend from end to end of said compound sections and are made of a width to fill the space 40 between the webs of said channel bars. They are shown as made of elongated cross section, the greater length being in the direction of the length of the holding bolts, and are made narrower than the spaces between the two 45 parallel rows of holding bolts of each compound section or unit.

The cores are placed between the channel bars of the compound sections before the nuts of the holding bolts are turned to their final 50 tightening positions. Thereafter the said nuts are tightened on the bolts and the pressure due to such tightening has the effect of 55 springing the marginal parts of the webs of said channel bars inwardly toward each other and of closely pressing together the inclined contacting faces of the flanges of the channel bars and I-beams. Under circumstances where practicable, the nuts of the holding bolts, of the compound sections are 60 not tightened until the simple sections interlocked therewith are driven and the cores are in place, thus permitting the sections to be readily interlocked and driven. The said cores, while advantageously made of wood, 65 may be made of other material found suit-

able for this purpose. An advantage of wood or like fibrous material is that contact of water therewith serves to expand the cores, which has the effect to spring the webs of the bars outwardly and to press the flanges of the interlocked units together for the purpose described.

It will be understood that my invention is applicable to sheet piling, the units or sections of which are made of rolled metal shapes or bars of other form and I do not wish to be limited to the illustrated construction, except as herein after made the subject of specific claims.

I claim as my invention:

1. Metal sheet piling comprising alternate units, one of which is a compound unit and having inwardly directed longitudinal guide flanges, bolts extending through the members of the compound units adjacent to the 80 side margins thereof to hold the same together, and means between said bolts coacting with the bolts, when the nuts of the bolts are tightened, to press the flanged margins of the members inwardly toward each other.

2. Metal sheet piling comprising alternate units, one of which is a compound unit, and having inwardly directed, longitudinal guide flanges, bolts extending through the members of the compound unit near their margins 95 to hold the same together, and cores occupying the space between the members of said compound unit and made of a width less than the distance between said bolts.

3. Metal sheet piling comprising alternate 100 units, one of which is a compound unit and having inwardly directed longitudinal guide flanges, bolts extending between the members of the compound unit near their margins to hold the same together and wood 105 cores occupying the space between the members of said compound unit and made of a width less than the distance between said bolts.

4. Metal sheet piling comprising alternate 110 simple and compound sections, the simple sections consisting of I-beams, and the compound sections consisting of channel bars arranged with their flanges directed inwardly toward each other and held together by bolts 115 extending through their marginal parts, and longitudinal cores extending between the webs of said channel bars and made of a width less than the distance between said bolts.

5. Metal sheet piling comprising alternate 120 units, one of which is a compound unit composed of plates fastened together by bolts and formed at their marginal parts to afford laterally interlocking and longitudinally 125 guiding engagement with adjacent units, said bolts extending through said plates of the compound unit and having angular parts which interlock with angular parts of the plates to prevent rotation thereof.

6. Metal sheet piling comprising alternate simple and compound units, the simple units comprising I-beams and the compound units comprising channel bars arranged with their flanges directed toward each other, said channel bars being held together by bolts extending through the webs thereof, and the flanges of the I-beams occupying the spaces between the channel bars and engaging the 10 flanges of said bars and interlocking engagement between the said bolts and the part

through which they pass to prevent bolts from turning when the nuts thereof are tightened or loosened.

In testimony, that I claim the foregoing as 15 my invention I affix my signature in the presence of two witnesses, this 30th day of August A. D. 1907.

GEORGE W. JACKSON.
